Primary Examiner—Bernard Ansher*Assistant Examiner*—Paula Mortimor[57] CLAIM

The ornamental design for a football necktie, as shown and described.

DESCRIPTION

FIG. 1 is a front elevational view of my new design for a football necktie;
FIG. 2 is a rear elevational view thereof;
FIG. 3 is a left edge elevational view thereof, the right edge elevational view being a mirror image; and,
FIG. 4 is a top plan view thereof, the bottom plan view being identical with the exception of the attachment of the straps.

FIG. 1

FIG. 4
